SNELLING MACHINE

Application filed September 26, 1931. Serial No. 565,365.

This invention relates to the so-called "snelling of fish hooks".

The objects of the invention are to provide a machine for the purpose, which will be as nearly automatic as possible and at the same time, be of relatively simple construction, practical and sturdy design and which, in particular, will accurately and uniformly apply the wrapping about the "gut" and hook shank and then operate to cut and tie such wrapping.

The many novel features of construction, combinations and relations of parts by which the foregoing and other important objects are attained will be understood from the following specification, considered in conjunction with the drawings accompanying and forming part of such specification.

The drawings illustrate one practical commercial embodiment of the invention, but it will be clear from the following that the structure may be modified and changed as regards this illustration, all within the true intent and broad scope of the claims.

Fig. 1 is a plan view of the machine and Fig. 2 is a side elevation of the same, the holder or guide for the gut being omitted in the first of these views; the shaft for supporting the same being indicated as broken away;

Figs. 3 and 4 are cross-sectional views of the machine as on substantially the planes of lines 3-3 and 4-4 of Fig. 2; Fig. 5 is a view looking at the right hand end of the machine; Fig. 6 is a broken longitudinal sectional view illustrating the hook carrying shaft and the differential screw feed for the winding mechanism; Fig. 7 is a broken sectional detail of the stop and start control shaft; Fig. 8 is an enlarged elevation of the left hand end of the machine; Figs. 9 and 10 are broken plan and vertical sectional views respectively of the wrapping, cutting and tying mechanism at the left hand end of the machine; Fig. 11 is a broken perspective detail of the hook holding, tying and cutting devices; Figs. 12 and 13 are broken sectional details of operating portions of the thread gripping device on substantially the planes of lines 12-12, 13-13 of Fig. 10.

In the several views, the hook is designated

15, the gut, snell, leader or line, 16, and the thread or wire, or strand of wrapping material, 17.

The hook is positioned in a chuck or holder on the end of a shaft 18 and shown as consisting of an axially located groove 19, in the half sectional forward end portion 20 of the shaft, receiving the shank of the hook, an overstanding, pivoted spring pressed lever 21, for holding the shank in such groove and an overstanding inverted V-shaped guide 22 for holding the looped end of the hook, Fig. 11. This confining guide provides with the channel 19, a socket for the barb end of the hook and such guide is shown as detachably secured at 23, to a head member 24, so that substitutions may be made for different sizes and shapes of hooks. The holding element 21 for the shank end of the hook is shown as pivoted at 25 in a head 26, on the half section end of the shaft 18 and as equipped with a handle extension 27, by which it can be shifted against the force of the spring 28. This chuck construction firmly holds the hook for the winding-on operation and at the same time, permits the hook to be readily removed and enables it being quickly secured in position.

The overstanding barb holding portion 22 of the hook chuck rotates with the shaft 18, but also has longitudinal travel imparted to it for effecting the necessary traverse for the winding-on operation. The head 24 carrying such portion of the chuck is therefore shown as mounted on the end of a tubular shaft or sleeve 29, surrounding shaft 18 and journaled in a suitable bearing 30, Fig. 10.

Advantage is taken of the sliding movement of head 24 to operate a knife for severing the wrapping material. As indicated particularly in Figs. 9, 10 and 11, this knife 31, is of generally semi-circular cross-section to fit about the half round portion 20 of shaft 18 and is carried by bracket 32, detachably secured to the face of head 24. The outer or active end of the knife slides through a segmental slot 33, in head 26, and the part which at times protrudes past said head is transversely slotted at one edge at 34, to receive the strand and effect severance of the

same as the knife is withdrawn in such head. The operation of this segmental knife through this slot also serves to slidingly key the two shafts 18 and 29 together.

6 The thread or strand is guided to a definite winding-on point by a suitable guide, shown in Figs. 2 and 8, as consisting of a thread tensioning device 35, adjustably secured at 36, on a supporting shaft 37, mounted on the base of the machine below and parallel to the hook carrying shafts.

10 The hook carrying shaft 18 is rotated in the illustration by a pulley 38, fixed thereon and which may be belt-driven direct from a small electric motor. The surrounding tubular shaft portion 29 is driven from shaft 18 through the keying engagement of the segmental knife 31, carried on the end of such tubular shaft and sliding through the head 15 26 on the end of shaft 18.

15 The traverse or winding-on feed of the concentric tubular shaft portion 29 is effected from shaft 18 as a result of the differential of two differently pitched screw sleeves 20 carried by and rotating with said shaft. The first or coarsely pitched screw sleeve is designated 39 and is shown in Fig. 6 as directly fixed to the drive pulley which is keyed to shaft 18. The second or more finely pitched screw sleeve 40 is shown in this same view as 25 slidingly keyed on the shaft at 41, in engagement at one end with the first screw sleeve and at the opposite end with a collar 42 on the inner end of the tubular feed shaft 29.

30 35 The two screw sleeves 39 and 40 are correlated to gain the differential effect by providing the two half nuts 43, 44, respectively engaged therewith and carried by a carriage 45, sliding on guide rods 46, 47. The latter is 40 shown as mounted eccentrically on the machine base by bearings 48 and as adapted to be rotated for the purpose of raising and lowering the carriage to mesh and unmesh the half nuts, by a strap 49, passing over the rotary hub portion 50 of a control handle 51. Fig. 3. A quick return spring 52 is shown in Figs. 1 and 2, acting on this carriage to 45 shift the same to the right when the handle 51 is rocked to release the half nuts from the screw sleeves.

45 The quick return movement of the carriage is utilized to return the second or sliding screw sleeve 40 and to snap the knife back to sever the strand, through the provision of a hook 53 on the carriage, positioned to engage back of the flange 54 on the collar 42 on the knife carrying sleeve or tubular shaft 29, as represented in Fig. 2.

50 On the forward or feed movement of the carriage, the knife is suddenly advanced, at the end of the wrapping action by engagement of a projecting lug or abutment 55, with the opposite side of the flange 54. This knife projector is shown as adjustably secured on

the carriage at 56, to take care of different lengths of wrap.

55 The outstanding flange 54 on the knife carrying shaft has an additional function, in that it is utilized to trip the machine at the end of the winding-on and knife projecting action. For the purpose, there is provided in the illustration, a handle 57 at the forward side of this flange connected with a rod 58, slidingly mounted in the frame and having 60 at the right hand end of the machine, Figs. 5 and 7, a shouldered or reduced portion 59, designed to allow a spring pulled hook 60 to drop into engagement with a stop shoulder 61, on the end of shaft 18, said rod also having a lever or cam portion 62, adapted when the rod is rocked right handedly to lift the hook 60 out of stopping engagement with hook rotating shaft 18.

65 The sliding control shaft 58 is shown in Fig. 7, as normally shifted toward the right by a spring 63, with the full rounded part of the same supporting the stop hook 60 out of engagement with the stop shoulder 61 on the hook rotating shaft and it will be evident that when this control rod is shifted to the left, the hook 60 will drop down over the shouldered portion 59 of the rod and hence be pulled by its spring 64, into holding engagement with the shoulder 61, to thereby 70 stop rotation of shaft 18 in definite position with the knife at the lower side of the shaft, the drive belt on pulley 38 slipping at such time, while the motor may continue in operation.

75 To enable adjustment for stopping the hook rotating shaft at the proper instant, the stopping handle 57 is shown as adjustably coupled to the sliding control rod 58 by a turn buckle connection comprising a 80 double-ended nut 65, reversely screwed at its opposite ends upon the collar 66, fixed on the rod and the hub 67 of such handle slidingly mounted on the rod. By rotating this turn buckle nut, it will be seen that the control handle may be readily shifted longitudinally of the rod without changing the position of the rod relative to the stop hook, a stop shoulder 68 on the left hand end of the rod insuring always the same definite position 85 of the rod as acted on by the spring 63, Fig. 7.

90 The knot tying mechanism is illustrated particularly in Figs. 8 to 13, and as there shown, comprises a pair of cooperating strand gripping fingers 69, adapted to enter into the hollow of the projecting knife blade. These fingers, as indicated in Fig. 11, are in the form of opposed tapered lateral projections on the upper ends of the blades or levers 70, pivoted horizontally at 71 between 95 the spaced parallel ears 72 on the upper end of a tubular post 73, which has at its lower end a hub 74, pivotally and slidingly mounted on a horizontal supporting rod or stud 75. A spring 76 is shown for rocking this gripper 100

post left handedly in Fig. 8 and for returning the same back against a stop shoulder 77, Fig. 10.

To rock the strand gripper toward the hook, that is right handedly in Fig. 8 and in the course of such movement, advance the same to carry the gripper fingers into the hollow of the projecting knife, there is provided a rotatably supported member 78 entered concentrically in the enlarged open end portion 79 of hub 74, and carrying a pin or projection 80, operating in an inclined cam slot 81 formed in the hub. Member 78 is shown as operated by a flexible pull 15 connection 82 extending partly thereabout and actuated for example, by a suitably located foot pedal. With depression of such a foot pedal connected with cable 82, it will be evident that through the cam construction disclosed, the gripper fingers will be rotated toward the winding-on axis and in such movement will be advanced longitudinally 20 into the hollow of the knife, to a position such as indicated in Fig. 11.

The parts are timed so that the knife blade will be projected a few turns before completion of the wrapping, so that as shown particularly in Figs. 9, 10, 11, the last few turns will be wrapped about the projecting 30 portion of the knife as indicated at 17a and the final turn will drop in the knife slot as indicated at 17b. This substantially radially extending portion 17b of the strand is the part which is gripped and held by the 35 gripper as the knife blade retracts to cut the strand and the return movement of the gripper then serves to pull this cut end portion outward beneath the last few turns to effect the "tie".

For operating the jaws of the gripper, there is mounted in the bore of the gripper post, a plunger 83, which as shown in Fig. 8, can enter between the opposed jaw members to in effect wedge them apart. A collar 84 40 slidably engaged on the post and acted on by spring 85, engages the lower ends of the jaw members to rock them in a closing direction against the spreading tendency of plunger 83, Fig. 8. The jaw opening plunger 83 is actuated in the rocking advancing movement of the gripper by the lower end of the same riding over a cam 86, Figs. 12 and 13. This cam is shown carried by a block 87, 45 slidably mounted in the bushing 88, which forms the bearing for the hub and as pressed to the right in Fig. 13 by spring 89. This sliding mounting of the jaw opening cam permits the cam to yield in the return movement of the gripper to prevent opening of the jaws as they draw out the strand and pull the last few loops closed about the same. In the forward or advancing movement, the plunger is obliged to ride directly up over the cam and hence the jaws are then positively 50 opened wide enough to surely pass about the

strand at 17b, where it extends substantially radially across the hollow of the knife and through the cutting notch in the edge of the knife. The cam 86 is relatively positioned to cause the jaws to open as they enter the hollow of the knife and to then snap closed over the strand. The path of movement of the plunger with respect to the cam is indicated generally by the broken line circuit 90 in Fig. 13, which shows how in the advancing movement, the plunger will step up and down over the cam projection to open and then close the jaws on the strand and will then permit the jaws to remain closed in the return movement of the gripper, there being sufficient freedom of movement as between the pin 80 and cam slot 81, to enable the plunger to pass back to the side of the cam projection as in Fig. 12, and the jaws thus to remain closed during the entire back stroke of the gripper. This inclined back stroke of the gripper also has the tendency to wrap the end which is caught under the final coils of the strand more tightly about the hook shank and attached gut.

For the purpose of accurately adjusting the relation of the gripper to the knife, the bearing sleeve 88 may be adjustably secured on the mounting shaft 75, as indicated at 91 and the rotatable cam pin carrying member 78, may have an adjustable mounting in the frame of the machine as indicated at 92.

To accurately determine the rocking and advancing movement of the gripper, a stop adapted to be engaged by the post of the gripper is indicated at 93, adjustably mounted at 94 on the supporting rod 37, Figs. 1, 2 and 8.

For positioning and guiding the gut or other element which is to be attached to the hook, a tubular guide may be provided, such as illustrated at 95, in Fig. 2, adjustably mounted on the outer end of the rigid supporting shaft 37. The latter is indicated as adjustably mounted at 96 on the base of the machine for permitting of simultaneous adjustment of all parts carried by the shaft and including in this instance, the snell guide 95, the limit stop 93 for the gripper and the strand positioning and tensioning device 35.

Operation

A hook is inserted in the hook chuck as indicated in Fig. 2 and a gut or snell is inserted through the positioning guide 95 into proper overlapping relation with respect to the protruding portion of the hook shank and a tie loop of the wrapping material is engaged about the end of the shank and the snell.

The machine is then started by rocking the starting handle 57 upwardly in Fig. 1 or toward the right as in Figs. 3, 4 and 5 to throw the hook 60 out of holding engagement with the stop cam 61 on the hook carrying shaft 18. This shaft thus released is

rotated by pulley 38 and the two screw sleeves 39, 40 turning therewith, effect a feed or traverse of the outer member 22 of the hook holding clutch so as to advance the winding along the overlapped portions of the hook shank and snell. This traverse movement is equivalent to the pitch differential of the two screw sleeves since the fixed screw sleeve 39 through half nut 43 tends to advance the carriage 45 at one speed and the half nut 44 on said carriage, engaging the finer pitch screw sleeve 40, cuts down such advance and pushes screw sleeve 40, through half nut 44 along the shaft at a rate of feed equal to such differential. This slidingly keyed screw sleeve by abutment with collar 42, forces the chuck sleeve 29 toward the left and the latter through head 24 slides the hook along in its positioning groove 19.

As the wrapping nears completion, the abutment 55 on the sliding carriage engages flange 54 and thereby provides a direct or higher speed connection between the sliding carriage and the chuck sleeve 29, advancing the latter at the full speed provided by the coarse pitch screw sleeve 39 and thus projecting the segmental knife 31 past the end of the hook shaft 18 to cause the last few turns of the strand to wrap about said segmental member and the final turn to drop in the cutting notch 34 in the edge of such member, as appears in Figs. 9, 10 and 11. As the parts reach this condition, the abutment flange 54 engages the starting handle 57 and carries the same with it towards the left in Figs. 1, 2 and 7 so as to shift control rod 58 and thereby permit the stop hook 60 to drop down over the shouldered portion 59 of the rod and hence engage the stop cam 61. This brings the hook carrying shaft to rest in the position shown in Figs. 2 and 6, with the knife at the underside of the shaft. Thereupon the pedal or other device engaged with connection 82, Figs. 8 and 10, is operated to swing the gripper jaws 70 toward the right in Fig. 8 and to advance them, through cam action 80, 81 into the hollow of the projected knife, the jaws opening to embrace and then closing upon the portion of strand in the cutting notch, as in Fig. 11 through cooperation of the jaw opening plunger 83 and cam 86. With the jaws thus gripped with the end turn of the wrapping, the handle 51 is turned left handedly in Figs. 3 and 4 to rotate the eccentric mount 47 of the carriage and hence disengage the half nuts 43, 44 from screw sleeves 39, 40.

Spring 52, Figs. 1 and 2, thereupon reacts to return the carriage back to the right hand position, ready for the next snelling operation and in such movement hook 53 on the carriage picks up the flange 54, drawing back the movable sleeve 40 into engagement with the end of fixed sleeve 39 and retracting the projecting notched portion of the knife so as

to "bite off" the strand by the cooperative action of the cutting notch in the knife guide 26 on the end of the hook shaft.

Return of the gripper is now permitted, as by removal of pressure on a foot pedal engaged with connection 82, whereupon spring 76 withdraws the gripper jaws on an incline from the position shown in Fig. 11 to a position corresponding to Fig. 9, the jaws remaining closed on the strand during this movement by reason of the cam arrangement 86, Figs. 12 and 13 so as to tighten the widened end loops down over this extracted end portion of the wrapping.

The snelled hook may then be slipped out of the chuck and the set of operations be repeated.

What is claimed is:

1. A hook snelling machine, comprising in combination, relatively rotatable hook holding and strand guiding means for serving a wrapping about overlapped portions of a hook shank and gut, or the like, and means for automatically severing and tying the wrapping at the end of such serving operation.

2. A hook snelling machine, comprising in combination, mechanism for serving a wrapping about overlapped portions of a hook shank and gut, or the like, and means for severing and tying the wrapping at the end of a predetermined serving operation.

3. A hook snelling machine, comprising in combination, mechanism for serving a wrapping about overlapped portions of a hook shank and gut, or the like, means for severing and tying the wrapping at the end of a predetermined serving operation, including a hollow knife having a cutting edge, means for advancing said knife to receive the final turns of the wrapping thereabout and for then retracting the knife to sever the wrapping material and a gripper adapted to enter the hollow of the projected knife and to withdraw the severed material through the final turns formed about the projected knife.

4. A hook snelling machine, comprising in combination, mechanism for serving a wrapping about overlapped portions of a hook shank and gut, or the like, means for severing and tying the wrapping at the end of a predetermined serving operation, including a hollow knife having a cutting edge, means for advancing said knife to receive the final turns of the wrapping thereabout and for then retracting the knife to sever the wrapping material and a gripper adapted to enter the hollow of the projected knife and to withdraw the severed material through the final turns formed about the projected knife, the cutting edge of the knife being provided by a cutting notch into which the last turn of the wrapping drops into position for engagement by the gripper.

5. A hook snelling machine, comprising

in combination, mechanism for serving a wrapping about overlapped portions of a hook shank and gut, or the like, means for severing and tying the wrapping at the end of a predetermined serving operation, including a hollow knife having a cutting edge, means for advancing said knife to receive the final turns of the wrapping thereabout and for then retracting the knife to sever the wrapping material, a gripper adapted to enter the hollow of the projected knife and to withdraw the severed material through the final turns formed about the projected knife and means for automatically positioning the parts for entry of the gripper into the hollow of the knife at the end of the serving operation.

6. In combination, a rotating hook carrier including means for advancing the hook as it is rotated to traverse a winding thereon and a winding severing means rotating with said hook carrier.

7. In combination, a rotating hook carrier including means for advancing the hook as it is rotated to traverse a winding thereon, a winding severing means rotating with said hook carrier, means for automatically stopping said hook carrier with the severing means in a predetermined position and a winding tying means for cooperative action with said severing means in the stopped position of the carrier.

8. In combination, relatively rotatable hook carrying and serving means, means for wide-looping a final turn or turns of the wrapping and a gripper for withdrawing the end of the wrapping through said loop or loops.

9. In combination, relatively rotatable hook carrying and strand serving means and differential screw mechanism for effecting relative traverse of said hook carrying and strand serving means.

10. In combination, relatively rotatable hook carrying and strand serving means, differential screw mechanism for effecting relative traverse of said hook carrying and strand serving means, including differently pitched screw sleeves rotatable together or shiftable one longitudinal with respect to the other and cooperating nut elements engaged with the respective sleeves.

11. In combination, a rotatable shaft for supporting a hook, a sleeve over said shaft rotatable therewith but movable longitudinally of the same, a hook engaging member on said sleeve for holding and advancing a hook supported by the shaft, a fixed screw member on the shaft, a differently pitched screw member rotatable with but slideable along the shaft for advancing the sleeve thereon and a travelling carriage provided with nut elements engaged respectively with the screw members.

12. In combination, a rotatable shaft for

supporting a hook, a sleeve over said shaft rotatable therewith but movable longitudinally of the same, a hook engaging member on said sleeve for holding and advancing a hook supported by the shaft, a fixed screw member on the shaft, a differently pitched screw member rotatable with but slideable along the shaft for advancing the sleeve thereon, a travelling carriage provided with nut elements engaged respectively with the screw members, a knife carried by the first mentioned sleeve; a member on the carriage for advancing said sleeve independently of the movable screw sleeve and means for releasing the carriage from the screw members and for returning said carriage and first mentioned sleeve to a starting position.

13. In combination, mechanism for serving a wrapping about overlapping portions of a hook shank and gut, or the like, and a hollow member projectable to receive a portion of such wrapping thereabout and notched for the entry of the wrapping.

14. In combination, mechanism for serving a wrapping about overlapping portions of a hook shank and gut, or the like, a hollow member projectable to receive a portion of such wrapping thereabout and notched for the entry of the wrapping and a retractable strand gripper adapted to enter the hollow of such notched member through the turns thereabout into holding engagement with the part of the wrapping in said notch.

15. In combination, mechanism for serving a wrapping about overlapping portions of a hook shank and gut, or the like, a hollow member projectable to receive a portion of such wrapping thereabout and notched for the entry of the wrapping and a guide with which the notched member cooperates to effect severance of the strand in the notch of the same.

16. In combination, mechanism for serving a wrapping about overlapping portions of a hook shank and gut, or the like, a hollow member, means for effecting the projection of the same to receive a portion of the wrapping thereabout, a strand gripper and means for effecting movement of the same toward and away from the wrapping receiving portion of the hollow projectable member.

17. In combination, mechanism for serving a wrapping about overlapping portions of a hook shank and gut, or the like, a hollow member positioned to receive a portion of the wrapping thereabout, a strand gripper and means for effecting movement of said strand gripper toward and away from the hollow of said hollow member.

18. In combination, mechanism for serving a wrapping about overlapping portions of a hook shank and gut, or the like, and a hollow member positioned to receive a portion of said wrapping thereabout and provided with a

cutting edge for severing the wrapping applied about the same.

19. In combination, mechanism for serving a wrapping about overlapping portions of a hook shank and gut, or the like, a hollow member positioned for receiving a portion of said wrapping thereabout and notched for the entry of a strand of the wrapping, means associated with said notched portion for severing a strand of the wrapping in the notch and means for effecting relative shifting of the hollow member and said last mentioned means to effect the severance of the strand.

20. In combination, mechanism for serving a wrapping about overlapping portions of a hook shank and gut, or the like, a hollow member positioned to receive a portion of said wrapping thereabout and provided with a cutting edge, a cooperating member associated with said cutting edge and means for effecting a strand severing relative movement of said cooperating member and hollow member.

21. In combination, relatively rotatable hook holding and strand guiding means for serving a wrapping about overlapped portions of a hook shank and gut, or the like and means for automatically severing the strand of the wrapping at the end of a predetermined severing operation.

22. A hook snelling machine comprising in combination, relatively rotatable hook holding and strand guiding means for serving a wrapping about overlapped portions of a hook shank and gut, or the like, strand tying means and means for effecting the operation of said strand tying means at the end of a predetermined serving operation.

23. In combination, a rotatable shaft member and associated strand serving means, a sleeve member rotatable with the shaft, said sleeve member and shaft member being relatively shiftable longitudinally in respect to each other, hook holding means carried by said members and strand severing means carried by said members and operable in the relative longitudinal shifting movement of said members.

24. In combination, a rotatable shaft member and associated strand serving means, a sleeve member rotatable with the shaft, said sleeve member and shaft member being relatively shiftable longitudinally in respect to each other, hook holding means carried by said members and strand severing means carried by said members and operable in the relative longitudinal shifting movement of said members and including a hollow severing blade carried by the sleeve member and a part carried by the shaft member and cooperating with said hollow blade.

In testimony whereof I affix my signature.
WALTER S. TORRENCE.
